UNDERGARMENT

Arthur R. Kneibler, Kenosha, Wis., assignor to
 Coopers, Inc., Kenosha, Wis., a corporation of
 Wisconsin

Application February 6, 1935, Serial No. 5,170

1 Claim. (Cl. 2—224)

This invention relates to undergarments, and more particularly to the type of undergarment known in the trade as "Shorts".

The main objects of the invention are to provide a garment of the type referred to, which will fit smoothly and snugly, while being exceptionally comfortable to wear; to provide such a garment with a built in jock strap or supporter construction forming a component part of the garment; and to provide a structure which may be manufactured economically so as to be adapted to be sold at low cost.

In general, it is the object of the invention to provide an improved garment of the type referred to, and other objects and advantages of the invention will be understood by reference to the following specification and accompanying drawing, wherein there is illustrated an undergarment embodying a selected form of the invention.

In the drawing—

Fig. 1 is a front elevation of the garment as it appears in flat folded condition;

Fig. 2 is a section on the line 2—2 of Fig. 1, showing the garment in distended condition as worn;

Fig. 3 is a section on the line 3—3 of Fig. 1 but showing the garment in the condition in which it appears when distended as worn;

Fig. 4 is a detail section on the line 4—4 of Fig. 2; and

Fig. 5 is a development of the component parts of the garment.

Referring now to the drawing, the improved garment herein contemplated embodies a waistband 10 of suitable elastic material, which is sufficiently soft and stretchable to be adjustable to the waist line without objectionable pressure on the waist line.

The body of the garment is formed by means of a central back piece 11, a central front piece 12, and side insert pieces 13 and 14.

The central front piece 12 is preferably of two-ply construction embodying plies 12^a and 12^b and said portion is formed with an integrally connected crotch extension 15 which embodies continuations of both plies 12^a and 12^b.

The central back section 11 has a substantially straight top edge 16 and its width is gradually increased downwardly so that its side edges 17, 18 flare outwardly, as clearly shown in Fig. 5. The lowermost portion of the back section 11 is provided with arcuate-shaped edge portions 18, 19 and a substantially straight bottom edge 19.

The arcuate edge portions 18, 19 constitute leg opening edges, as will presently appear.

The central front portion 12 is formed with a substantially straight top edge 20 and it is relatively narrow in width, as compared with the width of the back portion 11. The width of the central front portion also is gradually increased downwardly so that its side edges 21, 21 flare outwardly and downwardly. The crotch extension 15 is provided with arcuate side edges 22, 22 which result in a narrowing of the crotch extension relative to the width of the lower end portion of the central front section. The free end 23 of the crotch extension is also preferably substantially straight across its width.

The side pieces 13 and 14 approach a rectangular formation having substantially straight top edges 24, substantially straight, nearly parallel side edges 25 and 26 and bottom edges 27 of curved formation. The latter curved edges co-operate with the curved edges 18 of the back portion to form outer portions of leg openings designated 28. The curved edges 22 of the crotch portion 15 form inner edge portions of the leg openings 28.

As clearly indicated in the drawing, the substantially straight top edges 16, 20, 24, 24 of the respective sections are united to the lower edge of the waistband 10 by means of suitable stitching indicated at 29, the latter being preferably of a type which is stretchable with the elastic waistband. It will also be understood that the sections 11, 12, 13 and 14, made of knitted material, are also stretchable transversely of the direction of the ribs of the knitted fabric, although not materially stretchable longitudinally of said ribs.

The parallel side edges 25 and 26 of the side pieces 13 and 14 are respectively united by suitable means to the adjacent edges 21 and 17 of the central front and back pieces. The seams 30 between the front edges 25, 25 of the side pieces and the edges 21 of the front piece are designated 30 and the seams uniting the rearward edges 26, 26 of the side pieces and the edges 17 of the back piece are designated 31. The free end 23 of the crotch extension 15 is united to the lower edge 19 of the rear section by a suitable line of stitching indicated at 32. The seams formed by joining the sides of the central front portion to adjacent portions of the garment body form, in effect, reinforcements for the relatively inextensible central portion of the garment intermediate the crotch portion and the waist band. The firm support afforded the crotch portion from the waist band together with the tendency of the

crotch portion to snugly fit and conform to the anatomy results in a desirable body-supporting effect.

The length of the crotch extension 15 and of 5 the front portion 12 from which it depends is such relative to the length of the back piece 11 that the seam 32 is disposed well towards the back of the garment, i. e., nearer the plane of the back of the garment than that of the front 10 of the garment. This is considered an advantage, in that in such location, the seam offers the least interference with the comfort of the wearer.

The leg openings 28, 28 formed by the curved edges 18, 22 and 27 of the respective parts are 15 in this instance trimmed or finished by being hemmed. Within the hemmed outer leg opening portions formed at the lower edges of the back and side sections, there are disposed strips of elastic indicated at 33, 33, said strips being anchored in place in any suitable manner, but preferably by means of an expansible line of stitching designated 34 which engages only the upper marginal portion of the elastic strip. Such line of stitching 34 is preferably continued around 20 the entire leg opening to form the bottom edge. The inner margins of the leg openings are adapted to substantially coincide with the groins of the wearer and the outer margins extend upwardly substantially in line therewith.

30 In the central front piece 12, the ribs or direction of knitting extend up and down, and in the crotch extension, they extend lengthwise and substantially parallel with the leg forming edges 22, 22. Since knitted fabric is not materially extensible in the direction of its wales, it will be 35 apparent that the leg openings 28 are not materially extensible in their inner edge portions formed by said crotch extension. However, in the side portions 13 and 14 and in the back portion 11, the ribs of the fabric extend up and down and thus substantially transversely of the leg opening forming edges 18 and 27, so that said outer edge portions of the leg opening are extensible as permitted by the stretchability of the 40 knitted fabric. The inserted elastic elements 33, 33 serve to yieldingly maintain the leg openings in their contracted condition so that said leg openings may be proportioned to fit the wearer snugly by making such openings somewhat smaller than the corresponding portion of the average 45 person's thigh. Hence, a snug and smooth fit may readily be obtained by the described construction. The stretching of the outer marginal portions of the leg openings when the garment is worn, causes the inner marginal portions thereof to be drawn taut so as to avoid gathering or bunching thereof, and said inner portions are also thereby maintained in the groins of the wearer.

50 The two-ply construction of the central front piece 12 and crotch extension 15 and the longitudinal inextensibility thereof constitute said

5 portions a jock strap formation built in the garment. The elastic elements 33 exert a steady and substantial pull outwardly in a more or less horizontal i. e., forward and rearward and outward direction. This pull at the front of the garment is generally applied at the points where the seams 30 meet the leg-openings, so that the supporting part of the garment is maintained in tight-fitting condition and is prevented from wrinkling in an undesirable manner. The tension applied 10 by these elastic inserts also serves to maintain the back of the garment in snug-fitting position, and prevents the garment from bunching in the crotch.

15 The described arrangement has the further advantage that the seams 30, 30 and 31, 31 are so located as to be in positions where they are least conspicuous and least apt to press on and chafe the body of the wearer.

20 Further advantages of the described structure will be apparent to those skilled in the art, and changes in the structure may be made without departing from the spirit of the invention, the scope of which should be determined by reference to the following claim, the same being construed as broadly as possible consistent with the state of the art.

25 I claim:

30 A pair of men's shorts made of knitted material provided with an elastic waist band adapted to support the garment from the waist of the wearer, said garment having a knitted crotch piece the wales of which extend from front to back thereof so that said crotch piece is freely 35 inextensible transversely of the crotch but relatively inextensible longitudinally of the crotch, the longitudinally extending side edges of said crotch piece defining inner portions of the margin of the leg openings, the said side edges being of predetermined, substantially invariable length and coinciding with the groins of the wearer, the outer 40 portions of the margins of said leg openings extending upwardly substantially in line with the groins but transversely of the wales of the fabric, so that the fabric forming said outer portions 45 of the margins of said leg openings is freely extensible, elastic elements in said outer portions only tending to resiliently limit the size of said leg openings to substantially less than the leg size requirements, said outer portions and elastic 50 elements being expanded when the garment is worn so as to maintain said inner portions taut and in the groins of the wearer, the portions of the garment connecting the waist band with the crotch piece being relatively inextensible thereby to firmly support said crotch piece from the waist band, and the transverse resiliency of said crotch piece permitting the same to snugly fit the anatomy in resiliently conforming relation thereto.

55 ARTHUR R. KNEIBLER.
